HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

METHOD OF SIZING CURVED STEREOGRAPHIC PRINTING-PLATES AND APPARATUS THEREFOR.

1,134,800.

Specification of Letters Patent.

Patented Apr. 6, 1915.

Application filed December 10, 1914. Serial No. 876,497.

To all whom it may concern:

Be it known that I, HENRY A. WISE Wood, a citizen of the United States, residing at New York, in the county of New York and State of New York, have invented a new and useful Method of Sizing Curved Stereotype Printing-Plates and Apparatus Therefor, of which the following is a specification.

10 This invention relates to the method of and machine for cooling curved stereotype plates set forth in my application for Patent Serial No. 557,107 filed April 23, 1910, machine for cooling stereotype plates.

15 The principal object of this invention is to combine with the method of cooling set forth in said patent a method of bringing the plates finally to a definite and uniform curvature, which will work accurately with- 20 out minute supervision.

The invention also includes the mechanism for accomplishing these results.

Further features of the invention will appear hereinafter.

25 Reference is to be had to the accompanying drawings in which—

Figure 1 is a plan of a gravity cooling and sizing device constructed in accordance with this invention; Fig. 2 is a side view of the 30 same; Fig. 3 is a transverse sectional view on the line 3—3 of Fig. 1, showing the plate in its initial position in the cooling device; Fig. 4 is a sectional view on the line 4—4 of Fig. 1 showing the plate in its contracted 35 position; Fig. 5 is a plan similar to Fig. 1 showing a modified construction having a horizontal runway; and Fig. 6 is a sectional view of the same on the line 6—6 of Fig. 5.

When curved stereotype printing plates 40 are introduced into the finishing mechanism they usually retain a large part of the heat which they have had by reason of being cast from molten metal. They are clamped in the finishing mechanism and shaved out on 45 the interior as well as being machined in other places and this tends to heat up the plates still further but not in a uniform manner. When so clamped, of course, they are prevented from changing their size or 50 shape by contraction or expansion. In my above mentioned application for patent I have set forth a method of cooling such plates by which their interior surfaces are

cooled by water running on them directly without wetting the printing face. In carrying out that method I have found that the plates do not leave the cooling mechanism in an absolutely uniform condition as to diameter. Furthermore, plates that are dipped by hand for the purpose of cooling 60 are open to the same difficulty, which is a serious one because the plates must fit the printing cylinders with extreme accuracy. I have observed that if a plate is cooled only at its convex surface, its circle will 65 open up in response to the chilling and contraction which takes place first on the cooled side. Furthermore, if it is cooled simultaneously on both sides it will fairly well retain its original diameter, but there will 70 be variations in curvature depending upon whether the water reaches the outside first or last, and upon the relative amounts of water used on the two sides. In other words when a plate is wet simultaneously upon 75 both sides there are factors of variability due to the variations in the relative chilling effects of the water upon its two sides. These affect its final curvature and render the results of previous methods uncertain. 80 For the purpose of obviating these difficulties the variations are prevented according to the present invention by placing the plates to be cooled over a cooling saddle and providing surfaces adapted to engage the inner surfaces of the straight edges of the plates and located at exactly the right distance apart to give the plate the proper curvature if it is left substantially in contact with them when it is ready to be placed on the 85 printing cylinder. Furthermore, I cool the inner concave surface of the plate, as in my above mentioned patent, thereby contracting the plate so as to bring its edges into contact with the above mentioned surfaces. In 90 other words, these surfaces limit the contraction of the plates and the latter are contracted until their inner edges come to a definite distance apart. The plate is allowed to remain in contact with the sizing means 95 until practically all the heat has left it.

When the invention is applied to a gravity cooler the plate is cooled upon an inclined runway down which it is free to move by gravity as usual. Upon the water 100 being applied to its interior while the plate

is moving down the runway the plate contracts and its edges draw together suddenly, that is to say, in a space of time of about one second. In this way the edges of the plate 5 come into contact with the sizing surfaces and hold the plate in that position as long as it continues to cool on account of the cooling water. But when the plate has attained a substantially uniform and much 10 lowered temperature throughout its entire area I find that the contracting tension relaxes slightly. Thus the plate loses its grip on the sizing surfaces and it is free to slide down the runway by gravity to delivering 15 position. This is the only alteration which takes place in the sizing of the plate so far as I am able to observe after it has been sized in this manner. In this way it will be seen that the necessity of providing means 20 for stopping and starting the plate is avoided, the only thing necessary being to provide either a continuous water supply or to provide automatic means if desired for turning the water on when the plate comes 25 substantially into position to receive it and turn it off as the plate leaves this position. These later features, however, are not a part of this invention and therefore no means is shown for turning the water on or off.

30 Referring now to the drawings and first to Figs. 1 to 4 it will be seen that the invention is shown in these figures as applied to a gravity cooling machine which may be and preferably is, a part of the gravity shaving machine, although the shaving machine is 35 not shown herein. The machine is shown as comprising a frame 10 having an inclined top provided with an inclined runway formed by rollers 11 arranged on horizontal 40 axes and supported by the frame. The line of rollers is on a continuous incline from the top of the machine to the lower end. In the present instance each of these rollers is provided with a flange 12 on its inner end which 45 has an important function as will appear. Located between these rollers is a fixed saddle 13 over which the plates move as they travel down the runway. This saddle is shown, as in my above mentioned patent, as 50 of a hollow semi-cylindrical form connected with a source of water supply by means of a series of pipes 14. The outer convex surface of the saddle is provided with perforations 15 and with a series of riffle grooves 16 55 over which the water discharged from the inside through the perforations 15 runs in continuous unbroken streams without producing a spray. In this way the water does not touch the printing surfaces.

60 The effect of the water in cooling the plate is to engage the concave surface of the plate and thus cause the plate to contract. Its curvature is thus lessened immediately so that the edges of the plate which rest on the 65 rollers come nearer each other and engage

the flanges 12 thereof. These flanges are located at an exact and predetermined distance apart. This distance is equal to the desired inside diameter of the plate, and is measured from the outer side of the flange 70 on one side to the outer side of the flange on the other side. In this way the plate is allowed to contract until it engages these flanges, when it is held firmly. Obviously 75 the rollers are likewise held from rotation so that the plate cannot move along farther at this time. No matter how much more the plate would contract if left free to do so, it is clear that the contraction is thus positively limited. As the heat leaves the plate, 80 being conveyed away by the water, the plate gradually assumes a uniform temperature throughout so that its exterior and interior surfaces eventually come to the same temperature. This results in relaxing the tension 85 on the straight edges of the plate and in practice as soon as the plate is properly cooled the edges relax sufficiently to allow the rollers to rotate and the plate to slide down the rest of the runway by gravity. 90 I have found in practice that after the plate has been sized in this way and then slightly relaxed, no further appreciable changes in the size and shape of the plate occur, and that it is left in the condition in which it is 95 desired. In other words, it has the desired internal diameter and all the plates subjected to this action come out permanently of a uniform size so that they will fit the printing cylinders.

100 It will be understood, of course, that various shaving, trimming and other finishing means as well as drying means, if desired, can be employed with this machine and in addition to the steps of the method 105 set forth herein. These are not shown herein as they do not constitute a part of this particular invention.

Referring now to the form of the invention shown in Figs. 5 and 6, it will be seen 110 that the frame 10^a is provided with plain rollers 11^a for supporting the printing plate, and that the saddle 13^a is located between them as before, but now the plate is free to move on the rollers toward the sides of the 115 saddle. In this case the sides of the saddle itself are located at a proper distance apart to size the plate and the plate contracts against these sides, the effect being the same as in the other case. In this case the runway is shown as horizontal and the plate is moved on by hand or power until the plate 120 grips the saddle on account of the cooling action. When it is freed from it it is drawn or moved farther along in the same way.

I do not herein claim the method of, or apparatus for, cooling, independent of the sizing, as that is claimed in my above identified application.

125 In both forms shown the plate can be 130

stopped and started by mechanism if desired. For example, that shown in my previous British Patent 22,419, Oct. 10, 1906, can be used.

5 Although I have illustrated and described only two forms of the invention and shown the same as applied only to a single type of machine, I am aware of the fact that many modifications can be made therein and that 10 it can be applied to many other types of machines and that the method can be carried out with some modifications in the order of steps without departing from the scope of the invention as expressed in the claims. 15 Therefore, I do not wish to be limited in these respects, but

What I do claim is:—

1. A method of cooling a curved stereotype printing plate which consists in placing 20 said plate on a support located between the interior surfaces of the straight edges thereof, applying a cooling fluid to the interior concave surface of the plate to cool the plate and contract it until its straight edges engage 25 said support, whereby the interior of the plate will be contracted substantially to a fixed dimension.

2. A method of cooling a curved stereotype printing plate, which consists in applying 30 said plate to a support located between the inner surfaces of the straight edges of the plate, applying a cooling fluid throughout the concave surface of the plate, and protecting the convex printing surface of 35 the plate from contact with the cooling fluid, whereby the plate will contract substantially against said support.

3. The method of cooling and sizing a curved stereotype printing plate, which consists 40 in supporting the plate on its straight edges with opposite sizing surfaces inside the straight edges of the plate, cooling the interior concave surface of the plate to cause it to contract against said surfaces to bring 45 the interior diameter to a predetermined length, and continuing said cooling until the plate is cooled throughout and relaxes so as to cease to grip said surfaces, whereby the plate will be free to be removed.

50 4. The method of feeding, cooling and siz-

ing a curved stereotype printing plate, which consists in feeding it down an inclined runway, cooling its interior surface to cause it to contract and grip the runway so as to arrest its progress down the incline, and 55 continuing the interior cooling, whereby when the plate becomes chilled throughout, its grip on the runway will ease up and leave the plate free to move down by gravity.

5. The combination of a runway for 60 curved stereotype printing plates, means for cooling the concave surface of a plate while on the runway, and means for limiting the contraction of the plate.

6. The combination of a runway for 65 curved stereotype printing plates, means for cooling the concave surface of a plate while on the runway, and means for positively limiting the contraction of the plate while 70 on the runway and maintaining the plate at a definite size throughout the cooling operation.

7. The combination with a series of rollers for supporting the straight edges of a curved stereotype printing plate, said rollers having 75 flanges on their inner ends, of means for cooling the interior surface of a plate when resting on said rollers to first cause the plate to contract and its edges to engage said flanges for the purpose of limiting the internal diameter, and thereafter relax to release it therefrom.

8. The combination of two parallel series of rollers for supporting the straight edges of a curved stereotype printing plate, said 85 rollers having flanges, the outer edges of which are at a distance apart equal to the desired internal diameter of the plate, and means for cooling the plate on the interior only to cause the edges of the plate to contract against said flanges and size the plate 90 against them.

In testimony whereof I have hereunto set my hand, in the presence of two subscribing witnesses.
